(57) **CLAIM**

The ornamental design for an eyewear viewing device, as shown and described.

DESCRIPTION

FIG. 1 is a front perspective view of the eyewear viewing device in the present invention.

FIG. 2 is a rear perspective view thereof.

FIG. 3 is a side perspective view thereof.

FIG. 4 is a front view thereof.

FIG. 5 is a rear view thereof.

FIG. 6 is a top view thereof.

FIG. 7 is a bottom view thereof.

FIG. 8 is a left side view thereof; and,

FIG. 9 is a right side view thereof.

The eyewear viewing device in the present invention is an electronic eyewear viewing device having the appearance of eyeglasses or spectacles, and includes an eyeglass or spectacle frame, and an electronic viewer portion with a display for generating images for viewing by the wearer, and speakers for generating sound.

1 Claim, 5 Drawing Sheets
